UNITED STATES PATENT OFFICE.

MARVIN A. NICOL, OF WILLAMINA, OREGON.

MEANS FOR SECURING TIRES ON CRUSHING AND GRINDING WHEELS, ROLLS, AND THE LIKE.

1,138,399

Specification of Letters Patent.

Patented May 4, 1915.

Application filed May 8, 1914. Serial No. 837,223.

To all whom it may concern:

Be it known that I, MARVIN A. NICOL, a citizen of the United States, residing at Willamina, in the county of Yamhill and State of Oregon, have invented certain new and useful Improvements in Means for Securing Tires on Crushing and Grinding Wheels, Rolls, and the like, of which the following is a specification.

10 This invention relates to certain improvements in muller wheels and the like; and the objects and nature of the invention will be readily understood by those skilled in the art in the light of the following explanation of the accompanying drawings illustrating what I now believe to be the preferred embodiment or mechanical expression of my invention from among other formations, arrangements and constructions within the spirit and scope thereof.

15 An object of the invention is to provide improved means whereby the tires of wheels, rollers and the like, employed for grinding or reducing clay, ore, and other material, particularly in dry and wet pans and roller crushers, can be adjusted to cause uniform reduction of their wearing surfaces throughout the widths thereof.

20 A further object of the invention is to provide improved means for taking up the uneven wear of the circumferential surfaces of muller wheels due to the tendency of such surfaces to wear unevenly annularly thereof and thereby cause said surfaces to become curved transversely instead of maintaining them flat and cylindrical as required to attain the best results and highest efficiency.

25 A further object of the invention is to provide certain improvements in arrangements and constructions of parts and details for the production of improved and highly advantageous muller wheels, crusher rollers and the like.

30 The invention consists in certain novel features in construction and in combinations and arrangements as more fully and particularly set forth and specified hereinafter.

35 Referring to the accompanying drawings:—Figure 1, is a perspective view of a muller wheel embodying my invention. Fig. 2, is a diametrical section through the com-

plete wheel taken in the plane of the line 2—2, Fig. 3, is a detail-section taken in the plane of the line 3—3, Fig. 2. Fig. 4, is a perspective of the wheel with one rim section removed and shown separated from the wheel body and the other rim section, and with the rim section locking devices removed. Fig. 5, is a detail diametrical section of the two rim sections. Fig. 6, is a detail perspective.

In practice, muller wheels and the like, wear more rapidly at central or intermediate portions of their grinding or crushing surfaces than at the opposite end or edge portions thereof, and hence the circumferential or wearing surfaces of such wheels constantly tend to become transversely concaved, and thereby destroy the desired true cylindrical character of said surfaces. The grinding capacity of the pans, or other apparatus, in which muller wheels and the like, are employed is seriously reduced where wear destroys the cylindrical character of the circumferential surfaces of said wheels, and it is the particular object and purpose of this invention to provide improved means whereby the results of such uneven wear on the crushing or grinding surfaces of such wheels can be readily and economically corrected.

In the particular example illustrated, for purposes of explanation, I show the wheel comprising a body portion 1, equipped with a removable sectional tire forming the crushing or grinding surface of the wheel and, in this particular illustration, composed of two separate similar removable cylindrical rings or tire sections 2, arranged side by side on the body with their adjoining vertical side faces abutting midway between the opposite ends or outer side faces of the wheel. These two rings or tire sections are designed to be similar and alike in the matters of external and internal diameters and width or length so that when the two sections are brought together with their side faces abutting they will constitute a rim or tire having a true cylindrical wearing or peripheral operating surface, and these tire sections are so arranged on the wheel body and locked or secured, that they can be removed and re-

peared, or turned end 46 end, and again secured on the body so that the possibly crudely worn portions of their peripheral surfaces that formerly constituted the central portion of the tire surface, will then constitute the outer end or edge portions of said tire surface while peripheral surfaces of the tire sections not so badly worn will constitute said central or intermediate portion of the operative surface of the tire. The operative surface of the tire can thus be kept approximately flat or cylindrical throughout and caused to wear down approximately uniformly.

The wheel body is formed with an exterior cylindrical tire-receiving surface 10, of a diameter to snugly fit within the tire sections and of a length at least equal to the combined widths of the tire sections.

I show each tire section formed with a number of similar locking and tightening lugs 6, projecting from the inner diameter thereof and uniformly spaced around the circle thereof. These lugs are formed of the material of the tire sections or are rigidly fast thereto, and each lug is elongated in the direction of rotation of the tire end and is wedge-shaped at its rear end and is usually pointed or tapered forwardly from its rear end. The wedge shaped rear end of the lugs is preferably formed by the rearwardly interengaging inclined side faces 7.

The wheel body is formed with longitudinal peripheral grooves, channels, sockets or spaces 12, uniformly spaced around the circumference thereof and extending throughout the length of the body and at their ends opening through the opposite side faces thereof. The spacing and number of these channels correspond to the spacing and number of tire section lugs, and the channels are of such dimensions with respect to the lugs that the tire sections can be slipped endwise in and from the wheel body and can be moved longitudinally thereon with said lugs moving in and received by said channels and arranged transversely thereof. The wheel body is formed in its circumference with pairs of spaced parallel circumferential wedging or tapering grooves, depressions or sockets 14, arranged transversely with respect to the longitudinal axes of the channels and opening through side or edge walls thereof and all extending in the same direction from the channels and opening through corresponding edge or side walls thereof. Each channel has a pair of these grooves or sockets extending in the same direction along the circumference of the body and from a side wall of the channel and so arranged that there will be sockets for all the tire lugs and hence when the tire sections are slipped into place on the wheel body with their lugs in said channels, partial rotation of the tire sections on

the body will cause the tire lugs to slip into said sockets, while continued rotary pressure in the same direction will cause the lugs to become tightly wedged in said sockets and thereby tightly lock the tire sections to the wheel body. Sufficient rotary pressure in the opposite direction will cause the tire sections to partially rotate and bring their lugs from the sockets and back into the channels so that the tire sections can be moved longitudinally on and to and from the body. The lugs entering the sockets not only tightly center and seat the tire sections on the body but also lock the tire sections against longitudinal movement on the body and draw them tightly together with their vertical side faces in tight engagement.

Any suitable keys or other devices are provided for preventing accidental axial or rotary movement of the tire sections on the body in a direction to withdraw the tire lugs from the sockets. For instance, suitable removable keys or locking devices can be arranged in the channels behind the tire lugs to engage said lugs and prevent retrograde movement thereof from the sockets in which they are wedged.

In the particular example illustrated, I show several similar keying or locking devices, one for each channel, and each device consists of two end heads or blocks 16, forming cams or wedges, an intermediate cam block or wedge 17, and an adjusting or connecting bolt 18, whereby the end heads 16, can be drawn toward each other, or allowed to separate. These wedges and keying devices are arranged within the tire sections and extend longitudinally through the channels and fully occupy said channels behind the tire lugs with the wedging ends or faces of the blocks 16, 17, engaging the wedge or inclined rear faces of the tire lugs while the longitudinal edge walls of the channels opposite those through which the sockets 110 open form abutments for said devices.

The blocks 16, are formed with inner inclined faces 16^a, engaging the outer-side inclined faces of the ends of the lugs, while the blocks 17, are arranged between blocks 16 and engaging the inclined faces thereof and are also arranged between the pairs of lugs and are formed with inclined faces 17^a, engaging the inner inclined faces of the lug ends. The arrangement is such that when the blocks 16, of a keying device are drawn toward each other by tightening the connecting bolt 18, the inclined faces 16^a, will force the block 17, laterally against the tire lugs and the inclined faces 16^a, 17^a, will tend to force the tire lugs from the channels and into the sockets and thereby tightly lock the same to the wheel body and maintain the lugs wedged in the sockets and the tire sections locked to the wheel body.

By loosening or removing the connecting bolts 18, the keying devices can be knocked down or separated and removed from the channels to permit sufficient retrograde rotary movement of the tire sections on the wheel body, to bring the tire lugs into the channels and completely clear of the sockets so that the tire sections can be moved longitudinally on and from the body to reverse 5 70
 10 or otherwise shift their positions as before described. When the tire sections have been thus reversed or otherwise adjusted to the desired positions on the wheel body, the necessary rotary movement is imparted thereto 15 to carry their lugs far enough into the sockets provided therefor to clear the channels sufficiently for the introduction thereto and assembling therein of the keying devices. When the keying devices have been 20 assembled in the channels, they can be tightened up as hereinbefore described to drive the tire section lugs the necessary distance into the sockets to produce the desired tightness of the tire sections on the wheel 25 body and to maintain the tire sections locked against accidental loosening.

In the particular example illustrated, I show notches in the ends of the blocks 16, to receive and protect the nuts on the bolts 30 18. These notches are of sufficient width with respect to said nuts to permit application of a socket wrench thereto for rotating the same. These blocks 16, are intended to be drawn into the passages 12, until their 35 outer ends are approximately flush with the side faces of the wheel body. However, my invention is not limited to these details.

The tire sections can be adjusted back and forth, or reversed, from time to time as the 40 wear thereon tends to render the wheel wearing surface concave and hence the wheel wearing or operating surface can be kept approximately uniformly flat or cylindrical throughout until the tire is completely worn 45 out.

In the particular example illustrated, I show the wheel formed with a solid body having a central bore, with two bushings 20, inserted longitudinally thereinto from the 50 opposite ends thereof so as to almost meet at their inner ends leaving an annular lubricant space midway the length of the bore. The outer end portions of these bushings are formed with exterior annular flanges 21, to engage the center of the side faces of the 55 wheel body and limit the inward movements of the bushings and to form means whereby the bushings can be removably clamped or secured in the body. The bushings can be 60 secured by bolts 22, extending through the body and removably through holes in said flanges with nuts on the bolt ends and screwing against said flanges. The inner faces of these bushings are recessed to receive 65 anti-friction metal to form the bearing sur-

faces engaging the shaft or axle on which the wheel is mounted. When the bearings become unduly worn, the bushings can be removed and the anti-friction or bearing metal surfaces or bodies therein can be renewed and the bushings can then be reinserted in the bore of the wheel. The bushings can hence be used indefinitely and a material saving is thereby effected. 70

Any suitable means can be provided for 75 supplying lubricant to said bearing surfaces, although I show oiling hole 23, through which the lubricant can be supplied to the bearing. However, I do not wish to limit my invention to any particular hub or bearing formation. 80

I herein employ the term "wheel" in a broad sense to include rollers or other bodies having tires or rims and intended to grind, crush, or mull material. 85

It is evident that various changes, modifications and variations might be resorted to in the forms, constructions, and arrangements described without departing from the spirit and scope of my invention and hence 90 I do not wish to limit myself to the exact disclosures hereof. 95

What I claim is:—

1. In combination, a body having its periphery formed to removably receive an exterior annular member, said body having a channel extending longitudinally across its periphery and open at both ends of the body and an exterior inclined wedging depression in said periphery opening at one end into 100 said channel, and an exterior annular member fitting the periphery of said body and movable longitudinally thereon from either end in being applied to and removed from the body, said member having an internal 105 wedge-like lug rigid therewith and adapted to move in said channel when said member is being applied or removed, said lug adapted to wedge in said depression to exert radial pressure on said member under relative 110 rotary movement of the body and member in one direction and to move into the channel and from locking engagement with the depression under relative rotary movement of the body and member in the opposite direction. 115

2. In combination, a body having a cylindrical peripheral surface formed to removably receive an exterior annular member, the periphery of said body formed with a 120 wedging surface inclined circumferentially of the body, and an exterior annular member having a cylindrical inner surface to receive the periphery of said body, said member being movable longitudinally on said 125 body from either end thereof in being applied to and removed from the body, said member having an internal wedging surface rigid therewith and inclined circumferentially thereof and formed to directly 130

- engage said wedging surface of the body to lock and wedge the member against longitudinal and circumferential movements on the body under relative rotary movement of the body and member in one direction, and to move circumferentially from locking engagement with said surface of the body under relative rotary movement of the body and member in the opposite direction.
3. In combination, a wheel body or the like, having an exterior channel extending longitudinally across its periphery and open at both ends thereof and having a pair of parallel spaced depressions in its periphery extending laterally from said channel and having wedging floors, and a pair of separate annular members arranged on the periphery of said body and movable longitudinally thereon from either end thereof in being applied thereto and removed therefrom, said members being similar and each having a rigid internal lug movable longitudinally in said channel during the longitudinal movement of the members, said lugs adapted to enter said depressions and tightly wedge on the floors thereof to exert radial pressure on the members under relative rotary movement of the body and members in one direction and to relieve said radial pressure and move from said depressions and into said channel under relative rotary movement of the body and members in the opposite direction.
4. In combination, a wheel body or the like, having exterior channels extending longitudinally across its periphery and inclined spaced parallel depressions in its periphery extending laterally and all in the same direction from said channels, annular similar members fitting the periphery of said body and the separately removable therefrom and applicable thereto longitudinally from either end thereof, said members having rigid internal wedge-like lugs movable longitudinally in said channels during the longitudinal movements of the members on the body and adapted to move laterally with respect to the channels and into said depressions to exert radial pressure on and lock the members on the body under relative rotary movement of the members and body in one direction, and to move back from said depressions and into the channels to release the members from locking engagement with the body under relative rotary movement of the members and body in the opposite direction, and removable member-locking devices arranged in said channels to engage the channel walls and the lugs and cause said relative rotary movement of the body and members to lock the members on the body, said devices being removable from said channels to permit removal of said member, substantially as described.
5. In combination, a rotary body having a cylindrical periphery formed with exterior wedging surfaces inclined circumferentially of the body, similar separately removable exterior annular members on said periphery and each movable longitudinally thereon from either end thereof in being applied to and removed from the body, said members having internal wedging surfaces rigid therewith and inclined circumferentially thereof at their inner faces to directly engage said wedging surfaces of the body and exert radial pressure between the body and members to lock the members on the body under relative rotary movement of the body and members in one direction, and to move from locking engagement with said surfaces of the body under relative rotary movement of the body and members in the opposite direction, one of each pair of said surfaces being elevated and the other depressed to center the members and lock the same against longitudinal movement when the said surfaces are in locking engagement.
6. In combination, a body, annular interchangeable sections adapted to fit on said body and form an operating surface, said sections having internal lugs adapted to confine the sections tightly on the body under rotary movement of the sections, said lugs having wedge shaped rear ends, and removable locking devices between the body and inner faces of the sections having cam faces to engage said wedge shaped ends of the lugs to impart tightening rotary movement to the sections on the body.
7. A body, in combination with an annular member therefor composed of annular interchangeable sections having internal lugs, the body being channeled and grooved to receive said lugs, and removable locking devices fitting in the channels of the body to engage the rear ends of the lugs and comprising wedge blocks and connecting bolts, substantially as described.
8. A wheel body circumferentially formed to removably receive annular rim sections, in combination with removable rim sections, the body and sections having circumferentially arranged elevations and depressions adapted to interlock to normally maintain the sections against longitudinal displacement from the body, said sections being removable longitudinally from the body, and a longitudinally contractile locking and wedging device arranged between the body and sections and removable longitudinally thereof and comprising movable members and operating means.
9. A wheel body circumferentially formed to removably receive annular rim sections, in combination with removable annular rim sections, the circumferential portion of the body and the interior of the sections having opposing abutments, said sections and body

formed to normally interlock against longitudinal removal of the sections from the body, and a longitudinally contractile wedging and locking device removably arranged within the sections and between said abutments, and comprising members to engage said abutments and force said sections circumferentially on the body to locking posi-

tion and operating means therefor, substantially as described. 10

In testimony whereof I affix my signature in presence of two witnesses.
